DESIGN FOR A WHEEL

James W. Pattison, Detroit, Mich., assignor to
Kelsey-Hayes Wheel Company, Detroit, Mich.,
a corporation of Delaware

Application August 17, 1936, Serial No. 64,447

Term of patent 14 years

To all whom it may concern:

Be it known that I, James W. Pattison, a citizen of the United States of America, residing at Detroit, in the county of Wayne and State of Michigan, have invented a certain new, original, and ornamental Design for a Wheel, of which the following is a specification, reference being had therein to the accompanying drawing forming a part thereof, in which Figure 1 is a perspective view of the wheel body; Figure 2 is a fragmentary front elevation of the wheel; and Figure 3 is an axial section therethrough.

The present design comprises as the principal

and dominating features thereof that portion of the wheel body shown in full lines made convex and with two annular concentric beads and also with relatively narrow circumferentially extending openings therethrough; the radially outer bead having these openings; and also these openings being in the radially inner portion of the radially outer bead.

I claim:

The ornamental design for a wheel, substantially as shown and described.

JAMES W. PATTISON.
